US00D776216S

(12) **United States Design Patent** (10) Patent No.: **US D776,216 S**
(45) Date of Patent: **** Jan. 10, 2017**

(54) **GOLF CLUB HEAD**(71) Applicant: **PARSONS XTREME GOLF, LLC**,
Scottsdale, AZ (US)(72) Inventors: **Bradley D. Schweigert**, Anthem, AZ
(US); **Michael R. Nicolette**, Scottsdale,
AZ (US)(73) Assignee: **PARSONS XTREME GOLF, LLC**,
Scottsdale, AZ (US)(**) Term: **15 Years**(21) Appl. No.: **29/574,093**(22) Filed: **Aug. 11, 2016****Related U.S. Application Data**(63) Continuation-in-part of application No. 29/569,724,
filed on Jun. 30, 2016.(51) **LOC (10) Cl.** ..... **21-02**(52) **U.S. Cl.**USPC ..... **D21/752**(58) **Field of Classification Search**USPC D21/733, 752, 759
